US00D830626S

(12) **United States Design Patent** (10) **Patent No.:** **US D830,626 S**
(45) **Date of Patent:** **** Oct. 9, 2018**

(54) **ARC LIGHTER**

(71) Applicant: **Lianyungang Chudian Network Technology Co., Ltd.**, Lianyungang (CN)

(72) Inventor: **Rongya Gu**, Tongxing (CN)

(73) Assignee: **Lianyungang Chudian Network Technology Co., Ltd.**, Lianyungang (CN)

(**) Term: **15 Years**

(21) Appl. No.: **29/606,098**

(22) Filed: **Jun. 1, 2017**

(51) LOC (11) Cl. **27-05**

(52) U.S. Cl.

USPC **D27/141**

(58) **Field of Classification Search**

USPC D27/154, 139, 141, 152, 153, 156, 157, D27/159, 160; 431/273, 274, 277, 350, 431/353

CPC F23Q 2/00; F23Q 2/02; F23Q 2/16; F23Q 2/161; F23Q 5/00

(57) **CLAIM**

The ornamental design for an arc lighter, as shown and described.

DESCRIPTION

FIG. 1 is a bottom perspective view of the arc lighter with the top cap open;

FIG. 2 is a bottom perspective view of the arc lighter with the top cap closed;

FIG. 3 is a front elevational view of the arc lighter with the top cap open;

FIG. 4 is a rear elevational view of the arc lighter with the top cap open;

FIG. 5 is a left side elevational view of the arc lighter with the top cap open;

FIG. 6 is a right side elevational view of the arc lighter with the top cap open;

FIG. 7 is a top plan view of the arc lighter with the top cap open;

FIG. 8 is a bottom plan view of the arc lighter with the top cap open;

FIG. 9 is a front elevational view of the arc lighter with the top cap closed;

FIG. 10 is a rear elevational view of the arc lighter with the top cap closed;

FIG. 11 is a left side elevational view of the arc lighter with the top cap closed;

FIG. 12 is a right side elevational view of the arc lighter with the top cap closed;

FIG. 13 is a top plan view of the arc lighter with the top cap closed; and,

FIG. 14 is a bottom plan view of the arc lighter with the top cap closed.

1 Claim, 14 Drawing Sheets
